TROLLEY CONTACTOR

Frank H. Richterkessing, Louisville, Ky.

Application March 10, 1932, Serial No. 597,932

14 Claims. (Cl. 246—254)

My invention relates to the class of devices attached to or installed adjacent trolley wires to be engaged by a current collector carried by a car for the purpose of actuating signals, switches, recorders, etc., and are known in the electric railway industry as "trolley pans".

An object of the invention is to eliminate a number of the parts and a large part of the weight which have heretofore been regarded as necessary features in the structure employed to produce trolley pans as they are subjected to the elements, high electrical stresses and are called upon to withstand strains and shocks resulting from rapidly moving and flying trolleys.

Another object resides in the design developed so that major parts can be readily renewed and thereby salvage the remainder of the contactor which has heretofore been discarded when local damage had developed.

For an illustration of some of the physical forms in which the invention may take, reference is to be had to the accompanying drawings forming a part of this specification, in which—

Figure 1 is a longitudinal or side elevation of the short trolley pan. Fig. 2 is a long trolley pan built up of linear sections with a special form of reinforcement. Fig. 3 is another form of trolley pan constructed of units with a different form of metallic reinforcement. Fig. 4 is a cross-sectional view of Fig. 1 along the line 4—4. Fig. 5 is a cross-sectional view along the line 5—5 of Fig. 2. Fig. 6 is a cross-sectional view along the line 6—6 of Fig. 3.

In the drawings 10 indicates a tubular single section of insulating material such as a phenol-aldehyde condensation product and serves for the spine or backbone of the complete trolley pan as shown in Fig. 1, while three of such units are employed for structures in Figs. 2 and 3. In the latter cases they are linearly assembled and reinforced.

At the present period of commercial development in a phenol-aldehyde condensation product tubing the length shown in Fig. 1 is the longest standard piece of tubing that can be procured, the same length is used in the Figs. 2 and 3. This is not only simply a means of producing the long contactors which are necessary for certain types of service, especially where high speeds are encountered but it has the feature of admitting of renewing, at a relatively small cost, any one of the sections that may become damaged.

V formed bracket 11, on all of the contactors, is secured to the tubular member 10 by means of bolt 12, which passes through the center of the

tube, through perch 13 and inverted U shaped stop 14 thereby producing an inexpensive rigid light assembly. Said bracket and stop are each fashioned with an arcuate saddle to embrace tube 10 at the seat of contact. Flat spring 15 with its auxiliary reinforcement 15a is secured to bracket 11 by bolt 16 which also locates spacer block 17. Bolt 18 also passes through springs 15—15a and bracket 11 for the purpose of adjustably controlling the tension of spring 15 to stop 14. This whole assembly is referred to herein as a "spring unit", 30.

Angularly disposed contact flexible strips 19 are riveted to springs 15 and are disposed adjacent trolley wire 20 in order that the flanges of trolley wheel W will make suitable contact upon its passage through the trolley pan. In Figs. 1 and 3 a pair of strips are indicated whereas in Fig. 2, four contact flexible strips 25—26 are employed for the purpose of providing the trolley pan with directional means for energizing circuits and devices with which it can be installed.

In Fig. 2 the adjacent ends at 10a—10a of tubing 10 forming the spine are fitted into a metallic sleeve 27 through which bolt 28 passes and terminates in channel iron 29 which is also bolted at either end to the tubing by the bolts disposed in the tubing and securing the spring units to same. Suitable perches 31, 32 are provided to fit the tubing and form a very substantial bearing surface for the bracket.

In Fig. 3 in the adjacent ends at 10b—10b of the phenol-aldehyde condensation product tubing 10 forming the spine is disclosed a reinforcing tubing 35 which can be of metal or a phenol-aldehyde condensation product and extends for sufficient length to be engaged by the spring units shown in Fig. 5 thereby constituting a rigid and enduring whole.

As a means of attaching the trolley pans to guy wires and/or trolley wire ears, adjustable bolts 40—40 are provided which pass through the tubing and are located with reference to same by means of perches 41 or 42 to protect the tubing against being crushed under excessive strains, tubular reinforcements 43—43 similar to 35, however, of just sufficient length to accomplish the purpose, are disposed in the ends of the tubing.

This tubular contactor has been found to be of a type that can be readily produced and at a relatively low cost. In operating service it has proven its ability to withstand rigorous service even with its extreme lightness as compared with the contactor produced heretofore that could render comparable service.

The types shown are representative of some of the embodiments for this invention, obvious combinations, modifications (such as employing two parallel disposed tubes 10 to constitute the 5 spine or frame), and eliminations (omitting the contact strip 19 or strips 25, 26 from one side), staggering the strips (omission of one 25 from one side and one 26 from the opposite side) can be indulged in accordance with these teachings with- 10 out departing from the spirit of the invention, therefore, I wish to be limited only by the appended claims.

I claim:

1. A trolley pan constructed with a tubular 15 longitudinally extending frame formed of a phenol-aldehyde condensation product to which is attached contact means supported by an arcuate saddle.
2. A trolley pan constructed with a tubular 20 longitudinally extending frame formed of a phenol-aldehyde condensation product to which is attached longitudinally extending contact means supported by a pair of arcuate saddles.
3. A trolley pan constructed with a tubular 25 longitudinally extending frame formed of a phenol-aldehyde condensation product to which is attached longitudinally extending flexible contact means through a pair of extensions from arcuate saddles.
- 30 4. A trolley pan constructed with a tubular longitudinally extending frame formed of a phenol-aldehyde condensation product to which is attached yieldable longitudinally extending flexible contact means through a plurality of pairs 35 of extensions from arcuate saddles.
5. A trolley pan constructed with a telescopic tubular longitudinally extending frame formed of a phenol-aldehyde condensation product to which is attached an adjustable yieldable longitudinally 40 extending flexible contact means supported by an arcuate saddle.
6. A trolley pan constructed with a telescopic tubular spine of a phenol-aldehyde condensation 45 insulating material to which is attached yieldable longitudinally extending flexible contact means through a flexible extension from an arcuate saddle.
7. A trolley pan constructed with a tubular spine composed of metal and phenol-aldehyde 50 condensation insulating tubes to which is attached an adjustable yieldable longitudinally extending flexible contact means through a pair of flexible extensions from an arcuate saddle.
- 55 8. A trolley pan constructed with a telescopic tubular spine composed of a plurality of sections

of metal and phenol-aldehyde condensation insulating tubes to which is attached linearly disposed flexible contact means through a plurality of pairs of extensions from a plurality of arcuate saddles.

9. A trolley pan constructed with a telescopic tubular spine composed of a plurality of linearly disposed sections of metal and phenol-aldehyde condensation insulating tubes to which is directly attached, by an arcuate saddle, a yieldable 85 linearly disposed contact means.

10. A trolley pan constructed with a tubular longitudinally extending frame composed of a plurality of reinforced tandem sections of a phenol-aldehyde condensation product to which is directly attached, by an arcuate saddle, yieldable linearly longitudinally extending flexible contact strips, the contact faces of said strips being inclined with respect to each other.

11. A trolley pan constructed with a tubular 90 longitudinally extending frame composed of a plurality of reinforced tandem sections of a phenol-aldehyde condensation product to which is directly attached, by an arcuate saddle, a pair of yieldable longitudinally extending flexible 100 contact strips.

12. In a trolley pan, the combination with a trolley wire, of a longitudinally extending tubular frame of a phenol-aldehyde condensation material mounted thereon, a longitudinally extending 105 flexible contact means supported directly by said frame through an arcuate saddle, and a stop, attached to said frame by an arcuate saddle, said stop limiting the movement of said contact means toward said trolley wire.

13. In a trolley pan, the combination with a trolley wire, of a longitudinally extending tubular frame of a phenol-aldehyde condensation material mounted directly thereon by an arcuate saddle, a longitudinally extending flexible yielding contact means supported by said frame, and a stop, attached to said frame by an arcuate saddle, said stop limiting the movement of said contact means toward said trolley wire.

14. In a trolley pan, the combination with a 120 trolley wire, of a longitudinally extending tubular frame of a phenol-aldehyde condensation material mounted directly thereon by an arcuate saddle, a longitudinally extending adjustable flexible yielding contact means supported by said frame, and a 125 stop attached to said frame by an arcuate saddle, said stop limiting the movement of said contact means toward said trolley wire.

FRANK H. RICHTERKESSING. 130
